United States Patent Office.

W. G. WARD, OF NEW YORK, N. Y.

Letters Patent No. 94,458, dated August 31, 1869.

IMPROVEMENT IN BREECH-LOADING FIRE-ARMS.

The Schedule referred to in these Letters Patent and making part of the same.

To all whom it may concern:

Be it known that I, W. G. WARD, of New York, in the county of New York, and State of New York, have invented a new and useful Improved Breech-Loading Fire-Arm; and I do hereby declare that the following is a full, clear, and exact description thereof, reference being had to the accompanying drawings, in which—

Figure 1 is a central longitudinal vertical section;

Figure 2 is a bottom view of the breech-piece;

Figure 3 is a transverse section, taken in the dotted line *x* of fig. 1;

Figure 4 is a side view of a portion of the breech-piece; and

Figure 5 is an elevation of the firing-pin.

Like letters designate like parts in all the figures.

The nature of my invention consists—

First, in providing the breech-pin with two stops near its rear end, to prevent injury to the trigger-bolt or the slot of the breech-pin, during the operation of opening or closing.

Second, in forming the breech-piece with a projection or block on its under side, to take the shock of the recoil, and to give the trigger-bolt, which passes through it, more bearing-surface.

To enable those skilled in the art to make and use my invention, I will proceed to describe its construction and operation.

In the drawing—

A represents the stock, to which the breech-piece *B* is secured.

Inside of the breech-piece is the sliding breech-pin *C*, in which is a slot of the same construction, and for the same purpose, as shown in my patent dated June 29, 1869.

Near the rear end of the breech-pin, and opposite each other, are two quarter-segments, *a a*, which project beyond the periphery of the breech-pin, and in these segments are screw-threads, which fit into corresponding screw-threads on the inside of the breech-piece *B*.

On the periphery of the breech-pin, and between

the screw-segments *a a* and the handle *C'*, are two stops, *b b'*, which are located opposite each other.

In the top of the breech-piece *B* is an opening, which is closed by a sliding cover, *D*, when the piece is in position to be discharged. This cover is on top of the breech-pin *C*, and slides in a recess in the under side of the top of the rear end of the breech-piece.

As the breech-pin is turned, either to the right or left, the stops *b* or *b'* will strike against the edges of the sliding cover *D*, thereby limiting the extent of the turning of the breech-pin, thus preventing injury to the trigger-bolt, or to the slot in the breech-pin.

On the under side of the breech-piece *B* is a projection, *B'*, in which is an aperture for the trigger-bolt *E*. This projection fits into a recess, of corresponding form, in the stock *A*.

Heretofore, there has been a projection on the under side of the rear end of the barrel, to take the shock of the recoil; but the advantages of placing it on the breech-piece are, that it prevents it, and its connecting parts, from being loosened by the shock of the discharge, and also gives a larger bearing-surface, and a sure guide to the trigger-bolt.

F is a firing-pin, of the same construction as that used in my patent before referred to, with the exception that the spindle portion *F'* is fluted or grooved; as is also the trigger-bolt *E*, the object of this being to make it self-lubricating and self-cleaning as it is operated.

Having thus fully described my invention, What I claim as new, and desire to secure by Letters Patent, is—

1. The stops *b b'* on the breech-pin, when constructed and operated substantially as and for the purpose shown and described.

2. The combination of the recoil-block and fluted trigger-bolt, substantially as shown and described.

W. G. WARD.
